H. E. AUSTIN

HOLDER FOR CALENDARS, ETC

Filed Sept. 14, 1923

UNITED STATES PATENT OFFICE.

HARRY E. AUSTIN, OF CHICAGO, ILLINOIS.

HOLDER FOR CALENDARS, ETC.

Application filed September 14, 1923. Serial No. 662,670.

To all whom it may concern:

Be it known that I, HARRY E. AUSTIN, a citizen of the United States, residing at Chicago, in the county of Cook and State 5 of Illinois, have invented a new and useful Improvement in Holders for Calendars, Etc., of which the following is a specification.

This invention relates particularly to a 10 device adapted for holding loose sheets, strips, or cards. The improved device is well adapted for holding a pad of loose calendar sheets, but it may be employed for analogous purposes, such as for holding 15 shipping orders, shop orders, etc.

The primary object of the invention is to provide a simple and cheap device which is thoroughly adapted to its purpose, the retaining device of which can be readily removed 20 from or attached to the supporting base, thus enabling the pad of loose sheets to be removed or renewed at will.

The invention is illustrated in the preferred embodiment in the accompanying 25 drawing, in which—

Fig. 1 represents a perspective view of the improved holder equipped with a calendar pad; Fig. 2 a perspective view of the calendar pad removed; Fig. 3 a perspective view 30 of the retaining device of the holder; Fig. 4 a top perspective view of the base of the holder; Fig. 5 a bottom perspective view of said base; Fig. 6 a vertical, longitudinal, sectional view of the holder; and Fig. 7 a 35 transverse vertical section taken as indicated at line 7 of Fig. 6.

In the construction illustrated, A represents a base; B a self-clamping retaining device mounted on said base; and C a stack 40 of loose sheets, such as a calendar pad, engaged by the retainer B.

In the form shown, the base A comprises simply an elongated flat plate. This base may be of any suitable shape, however; 45 and it may be made of wood, glass, porcelain, or any other suitable material.

The retainer B is formed of a strip or length of resilient material, and preferably a length of fairly heavy gauge wire is employed. Brass or bronze wire is well suited to the purpose. The retainer B comprises a shank 1 which clampingly engages the base A, and arches 2 which form an extension of the shank and which rise from the base. 50 In the illustration given, the arches are disposed at right angles to the shank.

In forming the retainer B, the wire is first bent to form a loop 1^a; and the loop 1^a is then bent into substantially a U-form clamp having the upper members 1^b, the lower 60 members 1^c connected by the web 1^d, and the connecting end members 1^e. The members 1^b are extended and suitably shaped to provide the vertical arches 2. These arches have the free extremities 2^a which permit 65 the impaling of the leaves on the arches.

The base B preferably is provided on its upper surface with longitudinal grooves 3 adapted to receive the top members 1^b of the wire; at one end with the vertical 70 grooves 3^a adapted to receive the end members 1^e of the wire; and on the lower side with a longitudinal recess 3^b adapted to receive the clamping tongue which comprises the lower members 1^c and the connecting 75 web 1^d of the loop. At the upper side, the base is provided with keepers 4 which are in the form of perforations adapted to be engaged by the extremities 2^a of the wire arches. In the illustration given, the upper 80 grooves 3 are extended to intersect the upper ends of the perforations 4, but it will be understood that it is unnecessary that the grooves 3 should be of greater length than the top members 1^b of the loop-form shank 85 of the wire retainer.

While the clamping shank of the wire retainer is approximately of U-form, it will be understood from Figs. 3 and 6, that the tongue portion of the loop is initially sprung 90 upwardly somewhat, as illustrated in Fig. 3, so that a good clamping action will be obtained when the U-form shank is forced over the end portion of the base B which receives it. 95

In assembling the device, the sheets forming the pad may be caused to engage the arches, and the pad may rest upon the upper members 1^b of the clamping shank. The clamping shank may then be forced onto the 100 base plate in proper position, the tongue portion of the loop of the shank entering the recess 3^b, while the members 1^b engage the grooves 3 and the members 1^e engage the grooves 3^a. The members 1^b will spring upwardly sufficiently to enable the extremities 105 2^a of the arches to ride along the grooves 3 and finally enter the keepers, or sockets, 4. In effect, the base plate is provided with a socket suitably shaped to receive the various 110 members of the wire retainer, and such a socket taken in connection with the clamping

action, effectually anchors the wire retainer in position. It will be understood that the extremities 2^a of the arches depend a sufficient distance below the plane of the top 5 members 1^b of the clamping loop to enable said extremities to enter the sockets 4 to a sufficient depth to prevent any possibility of accidental dislodgment of the retainer.

The device described is simple, inexpensive, and may be readily assembled or disassembled. By employing a self-clamping retainer of the nature described, the base may, if desired, be made up of brittle material such as glass or porcelain; and it will 10 be understood that any desirable color or ornamentation may be given to the base. Moreover, the retainer may be removed and applied with great facility, thus enabling the calendar pad, or stack of loose sheets, 15 to be changed at will.

The foregoing detailed description has been given for clearness of understanding only, and no unnecessary limitations should be understood therefrom, but the appended 20 claims should be construed as broadly as permissible in view of the prior art.

What I regard as new, and desire to secure by Letters Patent, is:

1. A device of the character set forth comprising an elongated rigid base, and a retaining device clampingly mounted thereon comprising a resilient wire member having an elongated loop-form shank bent upon itself and slidably longitudinally with respect 30 to said base to clamp an end portion of the base between the upper and lower members of said shank, the upper members of said shank having formed integrally therewith arches upstanding from the base at 35 a substantial distance from the end of the base which is clamped by said shank, whereby the portion of the base which is clamped by said shank will serve to support a calendar pad.

45 2. A device of the character set forth, com-

prising a base provided at its upper surface with longitudinal grooves and at its lower surface with a longitudinal recess, and a retaining device comprising a resilient wire having a loop-form shank bent upon itself and clampingly engaging said base and withdrawable therefrom by movement longitudinally of the base, the upper members of the loop engaging said longitudinal grooves, and the tongue of the loop engaging said lower recess, said retaining device having arches forming extensions of the upper members of said loop and upstanding from said base.

3. A device of the character set forth comprising a base provided at its upper surface with longitudinal grooves and with socket-holes and provided at its lower surface with a recess, and a wire retaining device having a loop-form shank bent upon itself and clampingly engaging said base and having arches forming extensions of the upper members of said shank and upstanding from said base, the free extremities of said arches engaging the socket-holes, the upper members of said shank engaging said longitudinal grooves, and the tongue of said shank engaging said lower recess, said retaining device being capable of being applied to and removed from the base by longitudinal movement with respect to the base.

4. A device of the character set forth comprising a base, and a retaining device clampingly mounted thereon comprising a resilient wire having an elongated loop-form shank bent upon itself and clampingly engaging one end portion of said base and having arch-form extensions of the members of said loop upstanding from said base at an intermediate portion thereof, the free extremities of the members of said arches engaging recesses with which said base is equipped at an intermediate portion.

HARRY E. AUSTIN.
